UNITED STATES PATENT OFFICE.

ROBERT J. SIMPSON, OF ATHOL, MASSACHUSETTS.

POCKET TAPE.

1,415,489.

Specification of Letters Patent.

Patented May 9, 1922.

Application filed November 5, 1921. Serial No. 513,142.

To all whom it may concern:

Be it known that I, ROBERT J. SIMPSON, a citizen of the United States, residing at Athol, in the county of Worcester, Commonwealth of Massachusetts, have invented certain new and useful Improvements in Pocket Tapes, of which the following is a specification.

This invention relates to pocket tape 10 measure construction and the like, and particularly to a tape embodying certain features of construction by which great serviceability coupled with economy in manufacture is obtained. Pocket tapes of 15 the character described usually comprise a shallow cylindrical casing in which is lodged a flexible tape wound on a spring drum controlled by a releasable ratchet. The casings of these tapes have to be strong and light 20 and as the article is one intended for personal use, refinements in appearance and construction and finish are of considerable importance.

One characteristic defect of the ordinary 25 pocket tape measure has been the tendency of the members of the two-part casing to turn relative to each other with resultant liability of cutting or otherwise mutilating the tape at the delivery opening of the cas- 30 ing.

To the end therefore of providing a tape measure which will embody the above-named features of advantage and will not be open to the objection stated, I have devised my present invention. In it the members 35 of the two part casing are anchored against relative movement by a retainer which substantially encircles the case and is provided at its opposed edges with continuous channels within which the meeting edges of the casing members are adapted 40 to frictionally lodge. In addition to its retaining function, the channeled anchoring element assures accurate alignment of the casing parts without the necessity of 45 soldering, and stiffens the casing as well as providing a neat and smooth finish at this portion of the casing.

By my invention, I am thus able to produce a pocket tape measure of durable construction and neat finish at a very moderate manufacturing cost.

As illustrative of my invention I have shown in the accompanying drawings a 55 pocket tape in accordance with my invention. Throughout the specification and

drawings like reference characters are employed to indicate corresponding parts.

In the drawings:

Fig. 1 is a top view of a tape in accordance with my invention. 60

Fig. 2 an edge view of the shell.

Fig. 3 a section through the center of the shell with the central post left partly in elevation. 65

Fig. 4 is a view of the inner face of one shell.

Fig. 5 is a similar view of the other shell.

Fig. 6 is an edge view of the channel ring. 70

Fig. 7 a section fragment of the same.

Fig. 8 is an enlarged transverse section on the line 8—8 of Fig. 3.

Fig. 9 is a top plan view with the upper casing member of the two-part casing removed to expose the underlying tape drum, 75 and

Fig. 10 is a detail view of the push button, removed.

The pocket tape shown in the accompanying drawing comprises a pair of casing members 1 and 2. These are shallow cup-shaped members of sheet metal of the same diameter so that their edges 1¹ and 2¹ may be brought into registry. The member 2 has 80 centrally of its inner face a hollow post 3 which is riveted into the casing as shown in Fig. 3. The post 3 is slotted as at 4 to act as a guide for the arms 5¹ of a push button 5 which is guided in the central bore 3^a of 85 the post 3 and is backed by a coil spring 12 seated within said bore. The post 3 is also slotted as at 3¹ to receive the end of the motor spring 6 which is coiled within the drum 7. This drum 7 is an open ended 90 shell as appears in Fig. 3 and on it is wound a tape 8 the end being caught in the shell as indicated at 8¹.

The upper end of the post 3 is tapped to receive a screw 9 which passes through the central portion of the shell 1 thus drawing the two shells together. The coil spring 12 abuts this screw, as appears in Fig. 3. Between the shells 1 and 2 I interpose a ring 10. This spring while not constituting a 100 complete circle is very nearly so, being only less than a full circle by the amount of the width of the slots 11 which constitute the delivery opening through which the tape 8 is drawn. The ring 10 is channeled at both 110 edges at 10¹ to receive the opposed edges of the shells 1 and 2. This assures the align-

ment of the shells and permits them to be drawn up snugly together while at the same time affording a reinforcement and a smooth finishing surface to the shell edges.

5 In assembling the casing or drum member 7 with its motor spring 6 is slipped over the post 3. The push button 5 is then dropped into the axial bore of the post with the arms 5¹ bearing on the cam surfaces 7¹ which 10 are struck up from the metal of the casing. The spring 12 is then inserted in the post and the ring 10 laid on the upper edge of the shell 2. The shell 1 is then centered on the ring 10, its lower edge being lodged 15 in the upper groove 10¹. The screw 9 it then turned up and the shells forced tightly together.

Tapes so constructed are simple and capable of being readily made and quickly assembled. By reason of the ring, the shells 20 may be set tightly together and drawn up so that the wall of the casing 1 will have proper light bearing on the struck up portion 7² of the drum shell so that the shell 25 is kept in its proper position on the post 3 while being permitted to freely rotate under the action of its own motor spring or when the tape is drawn off.

Various modifications in details of structure may obviously be resorted to if within 30 the limits of the appended claims.

What I therefore claim and desire to secure by Letters Patent is:—

1. In a pocket tape, a casing comprising a

pair of shells, a central post on one shell, 35 a rotatable tape spool on said post, and an interposed strip of greater width than the thickness of the shell edges and channelled to receive the shell edges, and a screw engaging said central post and passing 40 through the other shell for drawing the shells together with their edges lodged in said channels.

2. In a pocket tape having a flexible tape member and spooling means for winding the 45 same, a casing comprising a pair of shells, each having a correspondingly notched edge, and a strip of greater width than the thickness of the shell edges and channelled to receive the edges, and extending between the 50 shell edges entirely around the shell from the edges of said notches, and means for drawing the shells together with their edges lodged in said channels.

3. In a pocket tape, a casing comprising, 55 a pair of shells and an interposed strip of greater width than the thickness of the shell edges and channelled to receive the shell edges, and means for drawing the shells together with their edges lodged in said channels. 60

In testimony whereof I affix my signature in presence of two witnesses.

ROBERT J. SIMPSON.
